[57] ABSTRACT

A device for holding a folded bedspread or serving as a clothing valet for draping clothing thereon having two substantially U-shaped frame members pivotably connected to each other at their ends, and means for holding or locking one of the frame members in a first position. One frame member extends between a mattress and box-spring and the other frame member is movable between the first position and second position wherein it extends out of the way beneath the box-spring when not in use.

FIG. 7

BEDSPREAD HOLDER OR THE LIKE

BACKGROUND OF THE INVENTION

It is well known in the art to construct collapsible bedspread holders, such as the type disclosed in U.S. Pat. No. 3,435,469. However, it will be appreciated that such devices and others heretofore available in the market have not been generally widely accepted inasmuch as they are relatively complex and generally require more involved mechanical mechanisms or arrangements of parts in order to function properly when in use. A further disadvantage of such prior art constructions is that they are heavy and relatively expensive to manufacture.

SUMMARY OF THE INVENTION

It is, therefore, a primary object of the present invention to provide a uniquely advantageous bedspread holder or the like of a construction of a type which is readily adapted for manufacture and assembly, and is capable of being fabricated at minimal expense, and which otherwise overcomes the above-mentioned difficulties of the prior art.

Another object of the present invention is to provide a bedspread holder or the like having the advantageous characteristics mentioned in the preceding paragraphs, which is extremely simple in structure, durable and reliable throughout its useful life, and one which is capable of economic manufacture and assembly to effect substantial savings in cost.

A further object of the present invention is to provide a bedspread holder or the like comprising substantially two lightweight elements or frame members, one of which extends between the mattress and box-spring, and the other of which is moved alternately between first and second positions.

It is still a further object of the present invention to provide an off-set on one of the members which serves to support the bedspread so as to provide clearance from the end edge of the bed.

Other objects and advantages of the present invention will become apparent upon reading the following specification and referring to the accompanying drawings, which forms a material part of this disclosure.

The invention accordingly consists in the features of constructions, combinations of elements, and arrangements of parts, which will be exemplified in the construction hereinafter described, and of which the scope will be indicated by the appended claims.

BRIEF DESCRIPTION OF THE DRAWINGS

FIG. 1 is a perspective view showing the bedspread holder or the like constructed in accordance with the teachings of the present invention, and parts thereon are indicated in dot dash lines so as to illustrate the invention as actually used when a first frame member is inserted between a mattress and box-spring;

FIG. 2 is a fragmentary side elevational view taken along the line 2-2 of FIG. 1 and showing the first frame member disposed between the mattress and box-spring;

FIG. 3 is a sectional view along the line 3-3 of FIG. 2;

FIG. 4 is a partial sectional view along the line 4-4 of FIG. 2;

FIG. 5 is a side elevational view similar to that of FIG. 2, but illustrating the second frame member in a second position;

FIG. 6 is an exploded perspective view showing the component parts of the pivoted connection between the ends of the two frame members; and

FIG. 7 is a fragmentary side elevational view of the bedspread holder shown in connection with a mattress and box-spring, and illustrating the second frame member retracted to a second position wherein it projects beneath the box-spring so as to be out of the way when not in use.

DESCRIPTION OF THE PREFERRED EMBODIMENTS

15

Referring now more particularly to the drawings, and specifically to FIGS. 1-5 thereof, a bedspread holder or the like is generally designated as 10 and includes a pair of frame elements having a substantially U-shape or configuration, and such frame elements are designated as 12 and 14. The substantially U-shaped frame members 12 and 14 are pivoted at their ends, as will be described hereinafter in greater detail. These frame members may be made of any suitable material, such as, tubular stock, rod material, or even flat material. However, it is desirable to construct the devices from hollow tubular stock material, such as lightweight aluminum tubing which preferably is of cylindrical construction, although square tubular construction would also be suitable.

As best shown in FIGS. 1 and 7, a first frame member 12 having a yoke or connecting portion 13 is inserted between a mattress 16 and its companion box-spring 18, as is usual with today's common footboardless beds.

35 The length of the legs 20, 22 connecting the yoke 13 and forming the first frame member 12 are of a sufficient length such that the device 10 is adequately held in a fixed position, both when the same is in use, as illustrated in FIG. 1 or when it is not in use as illustrated in FIG. 7. In the illustration of FIG. 1, a bedspread 24 is shown in dot dash lines as being suspended from the yoke or connecting element 26 of the second substantially U-shaped frame member 14. Suitable legs 28, 30 are connected at their ends to the legs 20, 22, of the first U-shaped frame member 12.

40 The yoke or connecting element 26 of the second substantially U-shaped frame member 14 is suitably offset from the legs 28, 30 so as to provide sufficient clearance room between the end edge of the bed thereby enabling a bedspread 24 to be easily draped over the yoke member 26 without interfering with the end edge of the bed or with the feet of an individual lying on the bed. Of course, such offset arrangement may be suitably accomplished by providing a bend, of say an acute angle in such frame member. In operation, it is preferred to employ a substantially right angle bend in the legs 28, 30 so that the yoke member 26 and the portions 29, 31 of said legs 28, 30 reside in a plane substantially perpendicular to the plane formed by the legs 28, 30.

45 Considering now in detail the ends of the substantially U-shaped frame elements, and as best shown in FIGS. 2-6, all of the ends of the leg members are provided with cooperating interfitting pivot elements 50 which includes means for maintaining or locking one of the frame members in a first position for holding or storing the bedspread when not in use, and retracting

a frame member to another or second position wherein the second frame member 14 projects beneath the box-spring so as to be out of the way when not in use. In this respect, FIG. 7 illustrates the offset yoke element 26 positioned beneath the bed frame 32 supporting the mattress and box-spring 16, 18 respectively. Means pivoting the second frame member 14 with respect to the first frame member 12 comprises a boss-like member 34 having flat side walls 36, 38 and such boss-like element extends inwardly from the ends of the leg members 20, 22 such that the flat sides 36, 38 are suitably vertically disposed. An aperture 40 is provided through such ends of the legs 20, 22 and such boss-like element 34 cooperates with a key hole type of recess 42 provided in the ends of the legs 28, 30 of the second frame member 14.

The key hole shaped recess 42 is provided with a cooperatively associated upper portion forming substantially flat side walls 44, 46 which cooperate together with the side walls 36, 38 of the boss-like element 34. Such ends of the legs 28, 30 are also provided with an aperture forming a through slot 48 for passage of suitable pin means 50 which is used in turn to loosely fasten together the ends of the frame members 12, 14. As best shown in FIGS. 3 and 4, a pin 50 is provided with suitable washer 52 and nut 54 for pivotably securing said ends of the frame members together.

In operation, the second substantially U-shaped frame member 14 is held in a first upward vertical position when the boss-like element 34 is positioned between the flat side wall surfaces, 44, 46 of the upper portion of the key hole shaped recess 42. When the second substantially U-shaped frame member 14 is to be retracted to its second position beneath the box-spring, it must be lifted upwardly so as to position the boss-like element 34 within the lower recessed portion of the key hole shaped recess 42, thereby enabling the second frame member 14 to be pivoted about the pin means 50. This second substantially U-shaped frame member 14 rotates substantially freely and readily so that it is completely out of the way when not in use.

In effect, the pivoting means includes a lock so that the frame members 12, 14 are fixedly retained in position when the boss-like element 34 resides within the upper recess portion of the key hole like recess 42. Upon withdrawal of the boss-like element 34 by lifting of the second frame member 14, the frame member 14 is then free to rotate about the pin means 50 to any position, such as the lower most position it is free to take due to gravity acting upon a freely pivotable member suspended about a suitable pivot axis.

It will be recognized that the device of the present invention is so designed that it is completely out of the way when not in use so that there are no extensions, or protuberances which would obstruct a user when making a bed or in using same. Further, when in use, the apparatus extends a relatively short distance beyond the foot of the bed so as not to interfere with convenient passage around the foot of the bed. Thus, the invention affords certain benefits in that it provides for the utilization of otherwise unusable space and furthermore provides for storing means and facilitates for the storing of a bedspread when not in use without the necessity of taking up additional floor space or wall space in one's bedroom. In a like manner, an alternate use for the invention may be to serve as a clothing valet,

namely to serve for draping clothing at the foot of the bed in the same manner that a bedspread may be draped as illustrated in FIG. 1 of the drawings.

From the foregoing, it will be seen that the present invention provides a bedspread holder or the like which is well adapted for manufacture and assembly, is extremely simple and reliable in construction, and economical in cost and which otherwise fully accomplishes its intended objects.

10 Although the present invention has been described in some detail by way of illustration and example for purposes clarity of understanding, it is expressly understood that certain changes and modifications may be made within the scope of the invention.

15 What is claimed is:

1. A holder for holding a bedspread and the like adapted to be used with a mattress and box-spring comprising: first and second U-shaped frame members each having a pair of legs pivotable connected to each other at the ends of said legs, and means comprising interfitting elements on each of the ends of said first and second frame members, for holding one of said frame members in a first position with respect to said other frame member, said first frame member when in use being adapted to be disposed at the end of a bed between said mattress and said box-spring, and said second frame member is free to pivot about the ends of said first frame member, the central portion of said second frame member connecting said pair of legs forming said U-shaped frame is offset by means of an angular bend in said second U-shaped frame member, said central portion of said second frame member being adapted to store said bedspread of the like by the draping of same over said central portion without interfering with the end edge of said bed or with the feet of one lying on said bed; said interfitting elements comprising, recessed means in the form of a keyhole type of recess having a generally circular recess and an intercepting rectangular recess, and including an elongated slot in said pair of legs of one of said frame elements, and boss-like means having a substantially flat-sided projection protruding from the ends of said other pair of legs of said other frame element and including an aperture centrally passing therethrough; and pin means maintaining said ends of said legs of said frame elements pivotably connected together.

2. The holder according to claim 1, wherein said angular bend is an acute angle.

3. The holder according to claim 3, wherein said angular bend is substantially a 90° angle.

4. The holder according to claim 1, wherein said frame members comprise substantially hollow tubular stock material.

5. The holder according to claim 4, wherein said tubular stock material is substantially cylindrical in section.

6. The holder according to claim 1, wherein said flat sided projections are cooperatively associated with said rectangular recesses for holding one of said frame members in a substantially vertically disposed position.

7. The holder according to claim 1, wherein said flat sided projections are cooperatively associated with said circular recesses for enabling said frame members to be pivotably connected to each other.
